UNITED STATES PATENT OFFICE.

ALBERT L. COLLIGNON, OF CHICAGO, ILLINOIS.

PNEUMATIC PLAYER-PIANO ACTION.

1,363,457.

Specification of Letters Patent. Patented Dec. 28, 1920.

Application filed March 26, 1919. Serial No. 285,350.

To all whom it may concern:

Be it known that I, ALBERT L. COLLIGNON, a citizen of the United States, residing at Chicago, in the county of Cook and State 5 of Illinois, have invented certain new and useful Improvements in Pneumatic Player-Piano Actions, of which the following is a specification.

My invention relates to improvements in 10 pneumatic player piano actions, and particularly refers to the usual type of pneumatic action in which there is a tracker bar provided with a series of openings connected by means of suitable tubing to a series of vacuum operated pneumatics.

The principal objects of my invention are to provide an improved construction in which necessary adjustments may be readily made to vary the stroke of the operative 20 parts comprising the action; to provide improved means for taking up the slack or lost motion in the various functional parts; to provide a construction in which the power controlling means, such as a valve actuating 25 member, may be separated or removed from the apparatus for inspection or repair; to provide improved means for mounting the various functional parts of the apparatus so as to facilitate repair or adjustment without disturbing other parts of the mechanism 30 and without destroying or disabling parts which are removed; to provide a construction which shall maintain its air tight character and shall remain fully operative and 35 efficient over a long period of years without the necessity of making frequent adjustments or repairs; to provide means automatically operative to prevent undue friction of the paper web on the tracker bar 40 during the times when the vacuum pressure is increased to emphasize portions of the composition which is being rendered; to provide an improved construction whereby access may readily be obtained to the bleed or 45 vent arrangement; to provide a construction which shall be simple and inexpensive in design and manufacture while being economical and efficient to maintain and operate; and, in general, to provide an improved 50 construction of the character referred to.

In the drawings accompanying this specification and illustrating a preferred embodiment of my invention, Figure 1 is a vertical section taken through the functional or operative parts of the apparatus; Fig. 2 is a front elevation of the apparatus, certain

parts being shown in section better to illustrate the construction, and Fig. 3 is a perspective view of the valve chest or housing showing detached therefrom the various 60 parts composing the valve seat and guide.

Referring now to the drawings, 10 and 11 represent the usual stickers which operate the hammers of the piano. Said stickers 10 and 11 are respectively operated by 65 means of upper and lower pneumatics 12 and 13, the pneumatics 12 being arranged in a horizontal or transversely extending series or bank above a similar series of the pneumatics 13. Inasmuch as the upper 70 pneumatics 12 and the lower pneumatics 13 are precisely similar in their mechanical construction and in operation, it will be necessary to describe only one set of parts 75 which comprise a complete operating unit for one of the pneumatics.

It will be observed that each of the pneumatics comprises a bellows 14 of thin rubber cloth or other suitable material, said bellows being connected between the stationary base part 15 of the pneumatic and the movable top board 16. Said top board 16 is provided at each end with an extension, the front extension 17 serving to operate a sticker by means of a projection 18 on the 80 latter, under which projection the tip of the extension 17 projects. It will be obvious that when the bellows of the pneumatic collapses as shown in the lower pneumatic in Fig. 1, the sticker will be elevated. It 85 will be understood that there is a hammer actuated by each of the stickers, as is customary.

In order to adjust the stroke of the sticker the tail extension 19 of the top board 16 95 of the pneumatic is equipped with a depending button 20 adjustably secured to said extension 19 by means of an adjusting screw 21, said adjusting screw 21 being provided with a flattened end portion 22 whereby it 100 may be readily turned so as to lower or raise the button 20 secured upon the lower end of the said screw 21. The lower face of the regulating button 20 is equipped with a suitable felt washer 23 which is arranged to 105 engage the flattened side 24 of a stop screw 25 inserted in the rear of the base board 15 of the pneumatic.

Similarly to adjust the slack or lost motion between the sticker and the operating 110 finger or extension 17 of the pneumatic, I equip said front extension 17 with a regulat-

ing button 26 similar to the regulating button 20, said regulating button 26 engaging the flattened end of a stop screw 27 inserted in the front end of the base board 15. It is obvious that by turning the screw 28 the button 26 may be lowered or raised so as to take up or adjust the lost motion between the sticker and the pneumatic in substantially the same way in which the stroke of 10 the device may be varied by means of the button adjusting screw 21 at the rear of the pneumatic. It will be observed that the ends of the adjusting screws 21 and 28 are in such a position that they are accessible at all times for adjustment purposes and that it is unnecessary to tamper with or remove any parts of the action in order to make such adjustment.

The pneumatics and other parts of the 20 piano action are supported by a horizontal transversely extending wind or vacuum channel, which channel is preferably formed of a length of sheet metal folded to form a U or a V shape in cross-section, as shown in 25 Fig. 1. As shown, the upper horizontal flange or fold 29 of the strip constitutes the upper wall of the channel and the lower inclined fold 30 constitutes the opposite or lower wall of the channel, the front wall of 30 which is formed by a member 31, removable for a purpose which will be described later. Said member 31 may extend throughout the entire length of the wind channel 32, or, if desired, it may be made sectional so as to 35 serve less than the entire number or series of pneumatics supported by each of the wind channels 32, in which case each section may be removed independently. In order to make the sides 29 and 30 of the channel 40 capable of resiliently expanding to admit the member 31 when assembling the device, the rear bend 33 may, if desired, be somewhat reduced in thickness so that the flexing of the metal will take place largely in the rear, 45 thereby maintaining the top wall of the channel substantially flat. It is, of course, understood that suitable flexible packing elements 34 and 35 are inserted between the member 31 and the edges of the channel in 50 order to maintain the joints air tight, the edges of the channel being drawn together by means of suitable screws 36 extending entirely through the top flange 29 and the member 31 and screwing into tapped holes 55 in the front edge of the bottom flange 30.

The pneumatic is not directly secured to the top of the channel 29, but is carried by the valve housing 37 which is directly mounted upon and secured to the top flange 29 of 60 the channel. Said valve housing 37 comprises an integral casting (as shown best in Fig. 3), preferably of some metal which is suitable for die casting, and is secured to the top of the channel by means of a set of 65 three mounting screws, two of which are in-

dicated at 38 and 39 in Fig. 1. The front of said valve housing 37 has a vertical face on which is a bushing like projection 40 inserted in an aperture 41 drilled in the complementary face 42 formed in the base board 70 of the pneumatic by cutting the front thereof to fit over the valve chest 37. The bushing 40 is apertured as shown at 43 and the base board 15 is apertured as shown at 44 in order to furnish an air passage between the 75 bellows 14 and the interior 45 of the valve chest. A pair of screws 46 extending horizontally through the rear portion of the base board 15 from the rear to the front thereof, are threaded into holes 47 tapped in 80 the rear face of the housing 37, and serve as means for securing and clamping the pneumatic to and in air tight engagement with the valve housing 37. In order to improve the seal and prevent leaks it will be understood that suitable rubber gaskets may be interposed between the casting 37 and the base 42 of the pneumatic base board 15. In the present instance such upper gasket may consist of a pair of folds of the same piece of 85 material which is employed for the bellows 14.

I will now describe the construction of the valve mechanism and associated parts.

Referring to the drawings, it will be observed that the valve 48, which may be constructed of wood or other light material is provided with integral upper and lower extensions or stems 49 and 50. The upper extension 49 of the valve may be guided in a 100 small plate or insert 51 secured in the under side of the front part of the base board 15 and underlying an aperture 52 in said base board. The aperture 52 is, of course, large enough to prevent interference with the upper end of the valve stem 49 when the valve rises. The lower end 50 of the valve stem is also guided in a small plate or strap guide 53, which is located below the valve and extends across and down an opening 54 in the 110 top flange 29 of the channel 32.

The valve 48 is provided with an upper facing 55 and a lower facing 56 of leather or other suitable material, which coöperate respectively with valve seats at the top and 115 bottom of the valve housing. The upper valve seat 57, surrounds an aperture 58 leading to the atmosphere through the slots 59, 60, and 61 in the top of the valve casting 37, the valve being normally not in engagement 120 with the said upper seat 57, unless the sticker is being operated. The lower valve seat comprises the upper surface of the metal washer 62, the under side of which is notched out slightly, as shown at 63, in order to admit the upwardly offset ends 64 of the valve guide 53, thereby holding said valve guide 64 securely in position. The said seat washer 62 is of the proper diameter to enter a recess bored in the under face of the valve 130

casting 37, a suitable gasket 65 being interposed between the bottom of the recess and the top of the washer 62 in order to furnish the necessary seal and prevent leaks. It will 5 also be understood that a gasket 66 of leather or other suitable material is interposed between the casting 37 and the flange 29 of the channel so as to prevent a leak existing in the joint between said parts.

10 The valve actuating member, in this instance the pouch 67, is carried by an extension 68 of the member 31, which may be called the pouch board. Said pouch 67, which may be of leather or other similar 15 material, extends over the shallow cylindrical pouch recess or cavity 69 and carries a small button 70 of cork or other suitable material which is located directly under the lower end 50 of the valve stem. It 20 will be observed by reference to the upper pneumatic shown in Fig. 1, that the top plane of the pouch is located slightly below the lower end 50 of the said valve stem so that whenever it is desired to remove the 25 pouch board such removal may be readily effected by simply withdrawing the pouch board toward the front, the valve not being affected. The pouch cavity 69 is connected to the corresponding hole in the tracker bar 30 of the piano, by means of a flexible tracket tube 71 fitted over an L-shaped pipe bend 72, a horizontal limb of which enters an aperture 73 communicating with the recess 69 through a vertically drilled aperture 74.

35 I will now describe the means for venting or bleeding the tracker tubes 71. Ordinarily such venting is effected by a small leak orifice which forms an obstructed or bleed connection between the vacuum in 40 the wind channel and the tracker tubes so that under normal conditions the tracker tubes contain air having substantially the same degree of vacuum as is present in the main wind channel. Such an arrangement 45 is open to the objection that when the suction in the channels is increased in order to emphasize a certain part of the musical composition which is being rendered on the piano, the vacuum effected in the tracker 50 tubes is correspondingly increased, which increase causes the paper web to press very tightly against the tracker bar, producing excessive friction and jumps in the continuous movement of the web.

55 In my improved arrangement the tracker tube 71 is bled or vented into an intermediate vacuum or wind channel the air in which, by means of an automatic regulating apparatus is maintained at a definite and 60 uniform vacuum pressure. To this end I interpose in the length of each of the tracker tubes 71 a metallic, vertically extending bleed section 75 rigidly supported in an aperture vertically, drilled in a trans-

65 versely extending horizontal member 76.

Said member 76 is of sufficient length to accommodate all of the bleed sections 75 and is grooved out, as shown at 77, at the rear thereof, to form a vent duct or chamber, the rear wall of which comprises the 70 back plate 78. It will of course be understood that a suitable packing element 79 is inserted between the vent housing 76 and the back plate 78 in order to prevent loss of 75 vacuum due to leaks.

The vent channel 77 is connected to one of the main wind channels 32 through a governing pneumatic or bellows designated as 80. Said governor pneumatic comprises a baseboard 81 suitably supported on the 80 vent member 76 and having an aperture or passage 82 formed therein and giving communication between the vent duct 77 and the interior of the bellows. The top board 83 of the regulator pneumatic is normally elevated by means of a coil spring 84 connected between a stationary hooked pin 85 and an adjusting screw 86 carried in the end or small arm or plate 87 extending from the pivotal end of the top 90 board 83.

Within the interior of the regulator bellows there is a wind box 88 mounted on the baseboard 81 of the pneumatic and having a rectangular chamber or cavity 89 which 95 is connected with one of the main wind channels 32 by a nipple or short tube section 90 and flexible tubing 91. The cavity 89 in the wind box 88 is otherwise closed with the exception of a valve opening 92 100 opening laterally through one of the vertical walls of the wind box into the interior of the bellows. Said opening 92 is capable of being closed by means of a knife valve 93 arranged to sweep over said opening 92 and pivotally supported on the pin 94 secured in the side of the wind box 88. The upper side of the knife valve 93 is formed with a semi-circular projection 95 arranged to be engaged by the under side 110 of the top board 83 of the regulator pneumatic, and said valve member 93 is normally raised into engagement with said top board by means of a small retraction spring 96, one end of which is hooked under the 115 knife valve as shown at 97, and the other is passed around a pin 98.

Each of the bleed sections 75 is individually vented into the main vent duct 77 by means of any desired form of vent cups, one 120 of which is indicated at 99 in Fig. 1, said vent cup being pressed into a horizontal aperture 100 communicating with the tube section 75 and having the usual vent orifice 101. It will be observed that whenever occasion arises to clean or repair the vent cup or cups, access may be obtained by simply removing the back plate 78 after taking out the securing screws 102.

125 I will now describe the operation of the 130

above described parts. It will be understood that suitable vacuum-producing arrangements, such as a motor driven pump or a foot-operated bellows, is connected to the usual apparatus for regulating the vacuum pressure, it being also understood that by means of manually operated keys or other devices the vacuum pressure which is conducted to the main wind channels 32 through the pipes 75, may be varied at will in order to produce the desired variations in the loudness or volume of the music; hence variations will exist in the vacuum pressure contained in the wind channels 32, tube 91, bushing 90 and cavity 89 in the wind box 88. Said variations and pressure will not, however, be transmitted to the vent box or channel 77 because whenever the vacuum tends to increase within the bellows 80, pressure of the atmosphere will depress the top board 83 of the bellows 80 against the tension of the springs 84 and 96, thus resulting in a closing or a partial closing of the valve opening 92. Therefore, the degree of vacuum in the main vent duct 77 will be substantially uniform regardless of variations in the main vacuum which operates the note pneumatics.

The note pneumatics 12—13 operate in substantially the same manner as in any standard player piano action. When the tracker tube 71 is opened to the atmosphere by reason of one of the note apertures in the traveling paper web registering with the corresponding aperture in the tracker bar, air rushing down the tracker tube 71 and into the pouch cavity 69 will raise the pouch 67 and elevate the valve 48. Thereupon the opening in the upper valve seat 57 will be closed, thereby preventing atmospheric air from entering the bellows of the note pneumatic; while at the same time the valve will be raised off the lower valve seat connecting the vacuum channel 32 with the interior of the bellows; hence the top board 16 of the pneumatic will snap down into the position shown in the lower part of Fig. 1 and the sticker will be operated.

While the opening in the tracker bar is exposed to the atmosphere, the top board will be maintained in pressed condition and the note will be held. As soon, however, as the paper web covers the hold in the tracker bar, the air in the tracker tube 71 will be vented into the vent channel 77 through the bleed orifice 101, and the pouch cavity 69 will be exhausted until it contains insufficient pressure to hold up the pouch 67 and the valve 48. The valve will then drop from the upper to the lower seat, allowing atmospheric air to enter the bellows 14 and cutting off its communication with the vacuum channel 32.

The detailed description of the various parts is not intended to be any limitation

upon the scope of the invention, which is to be determined by reference to the appended claims, construing the latter as broadly as possible consistent with the state of the art.

70 I claim:

1. In a pneumatic player piano the combination of a transverse series of sticker actuating pneumatics, a transversely extending wind channel common to said series of pneumatics, a mounting removably inserted in and closing one side of said channel, and a valve actuating member carried by said mounting.

75 2. In a pneumatic player piano action, the combination with an exhaust chamber and a sticker actuating pneumatic thereabove, of a valve housing detachable from and interposed between the exhaust chamber and pneumatic and containing a valve for controlling communication therebetween.

80 3. In a pneumatic player piano action, the combination with an exhaust chamber and a sticker actuating pneumatic of a valve housing interposed therebetween and independently removable therefrom, said valve housing containing a valve controlling communication between the exhaust chamber and the pneumatic.

85 4. In a pneumatic player piano action, the combination of an exhaust chamber having a valve housing detachably mounted thereon and containing a valve for controlling the inlet to the exhaust chamber, and a sticker actuating pneumatic detachably mounted on the housing and communicating through the valve housing with the exhaust chamber.

90 5. In a pneumatic player piano action, the combination of an exhaust conduit comprising a plate bent in a U-shape, a mounting inserted in and closing the open end of the U-shaped plate, a valve housing mounted on one of the arms of the U-shaped plate, a sticker actuating pneumatic controlled by said valve, and means on the aforesaid mounting for regulating the operation of the valve.

95 6. A pneumatic player action comprising a transversely extending support, a pneumatic bellows detachably mounted on top of said support and communicating therewith, a valve housing detachably interposed between the support and bellows and having a valve for controlling communication therebetween, a wind channel under said support, a pouch board removably inserted in said channel, a valve actuating member carried by said pouch board and means extending through said support whereby said valve actuating member may actuate said valve, said means being secured to said valve and extending through said support.

100 7. A pneumatic piano action comprising a valve housing having a valve containing

130

135

cavity therein, a sticker-actuating bellows superposed above and provided with a baseboard detachably secured to said valve housing, said cavity communicating with 5 said bellows, said valve housing being provided with upper and lower openings and upper and lower valve seats surrounding said openings, the upper opening leading to the atmosphere, a wind channel below said 10 valve housing and provided with a wind conduit communicating with said lower opening, and a member detachably secured in said wind channel and provided with means for actuating said valve.

15 8. In a pneumatic player piano action, the combination of an exhaust chamber and a sticker actuating pneumatic mounted side by side and having a recess therebetween and a valve housing mounted in said recess 20 so as to be independently removable from the exhaust chamber and sticker actuating pneumatic and provided with a valve for controlling communication between the exhaust chamber and the sticker pneumatic.

25 9. A pneumatic player action comprising a row of sticker actuating pneumatics, a support therefor comprising a wind channel, a valve housing carried by said wind channel, a valve in said valve housing provided 30 with an operating stem extending into said channel, a pouch board removably secured in, and forming a side closure of the said channel, said pouch board having an inner extension the upper surface of which is located below said valve stem, and a pouch on 35 said board provided with a valve actuating button separated from and adapted to elevate said stem.

10. In a pneumatic player action, the combination with a sticker, of a pneumatic for 40 operating the sticker, comprising a fixed base, a member pivoted at one end of the base, a bellows interposed between the pivoted member and base for operating the former, and an operating arm on the movable member at the opposite side of the pivot from the bellows engaging and operating the sticker.

11. In a pneumatic player piano action, the combination of a pneumatic comprising 50 an elongated stationary base and a corresponding member pivoted thereto at one end, a bellows interposed between said base and member, a sticker operated by the member, and adjustable means at each end of the pneumatic serving to stop the opening and closing movements of the bellows.

12. In a pneumatic player action, the combination of a horizontally extending series 60 of pneumatics, a horizontal vacuum chamber extending below said pneumatics and provided with an upper wall on which said pneumatics are mounted and provided with a lower wall resiliently connected to said 65 upper wall, a valve operating member in

said channel, and a support for said member insertible between said walls.

13. In a pneumatic player action, the combination of a horizontally extending series of pneumatics, a horizontal vacuum chamber 70 extending below said pneumatics and provided with an upper wall on which said pneumatics are mounted and provided with a lower wall resiliently connected to said upper wall, a valve operating member in said 75 channel, and a support for said member insertible between said walls, the arrangement including means for simultaneously clamping said support into tight-fitting engagement with both of said walls. 80

14. In a player mechanism of the class described, the combination of a pneumatically operated device, an exhaust chamber in which the degree of exhaustion is varied, connections for operating said device by the 85 pressure of the exhaust chamber, means for timing the operation of the device thereby, and automatically operated means connected with the exhaust chamber for maintaining a uniform condition of pressure on said 90 means with a variable degree of exhaustion in the exhaust chamber.

15. In a player action, the combination of a tracker tube, a pneumatically operated 95 player mechanism communicating with a variably exhausted chamber, a valve mechanism controlled by the degree of vacuity in the tracker tube for regulating communication between the variably exhausted chamber and the pneumatic player mechanism, and 100 means connecting the variably exhausted chamber with the tracker tube whereby a uniform degree of vacuity is maintained in the tracker tube by a variable degree of exhaustion in said chamber. 105

16. In a player action, the combination of a plurality of pneumatically operated player mechanisms, a plurality of tracker tubes for controlling said mechanisms, a main vacuum chamber adapted to be varyingly exhausted to diminish or intensify the action of the pneumatic player mechanism, an auxiliary vacuum chamber connected with the tracker tubes for exhausting the air therefrom, and exhausting means for the auxiliary vacuum chamber suitably connected with the main vacuum chamber so that a uniform degree of vacuity is maintained in the former by a varying degree of vacuity in the latter. 110 115

17. In a pneumatically operated player mechanism, pneumatically operated means for timing the operation of said mechanism, a chamber from which the air is variably exhausted so as to increase or diminish the 125 intensity of the action of the pneumatically operated mechanism, means connecting said chamber with the aforesaid pneumatically operated means to exhaust the air therefrom and having a pressure regulator whereby 130

the variable degree of vacuity in said chamber maintains a uniform rate of vacuity in the pneumatically operated means.

18. In a pneumatic action for musical instruments, the combination of a vacuum chamber having a yielding diaphragm therein, a pneumatic connected with the chamber at one side of the diaphragm through a

valve mechanism controlled by the diaphragm, and a tracker tube having uninterrupted communication with the chamber at the other side of the diaphragm and provided with means for exhausting the air therefrom.

ALBERT L. COLLIGNON.
